United States Patent Office

Des. 195,483
Patented June 18, 1963

195,483

GRILLE

Edward C. Hallock, 86 Woodland Ave., Summit, N.J.

Filed Apr. 25, 1962, Ser. No. 69,850

Term of patent 14 years

(Cl. D54—2)

FIG. 2.

FIG. 1.

Des. 195,483

PAGE 2

FIG.3.

FIG.4.

I claim:

The ornamental design for a grille, as shown.
